(57) **CLAIM**

The ornamental design for an automobile tire, as shown and described.

DESCRIPTION

FIG. 1 is a front, elevation view of an automobile tire showing my new design;

FIG. 2 is a rear, elevation view thereof;

FIG. 3 is a left-side, elevation view thereof;

FIG. 4 is a right-side, elevation view thereof;

FIG. 5 is a top, plan view thereof;

FIG. 6 is a perspective view thereof;

FIG. 7 is an enlarged cross-section view taken along the line A—A in FIG. 1, in the part C—C of FIG. 4; and,

FIG. 8 is an enlarged view of the part B1—B2 in FIG. 1.

The broken lines in the drawings illustrate environmental structure and form no part of the claimed design.
